UNITED STATES PATENT OFFICE.

ALLEN A. TIRRILL, OF SCHENECTADY, NEW YORK.

SNAP ELECTRIC SWITCH.

No. 819,822.

Specification of Letters Patent.

Patented May 8, 1906.

Application filed September 26, 1904. Serial No. 225,960.

To all whom it may concern:

Be it known that I, ALLEN A. TIRRILL, a citizen of the United States, residing in Schenectady, in the county of Schenectady and State of New York, have invented certain new and useful Improvements in Snap Electric Switches, of which the following is a specification.

This invention is designed to contribute to the convenience and efficiency of operation of that type of switch shown in application filed December 11, 1902, Serial No. 134,850, and to supply to said switch a fuse device which will be easy of manipulation, thoroughly reliable in its action, and unlikely in any emergency to smoke or otherwise mar the ornamental exterior of the switch.

The invention will be described herein in connection with an improved snap-switch designed to be placed on a ceiling and to be operated through a depending cord or chain, successive pulls on which alternately make and break the circuit. All discussion of possible modifications will be omitted until the specific mechanism has been fully described.

In the drawings, Figure 1 is a side elevation of the driven contacting parts of the switch. Fig. 2 is a transverse section along the line 2 2 of Fig. 1. Figs. 3 and 4 are respectively a side elevation and a front elevation of one of the brackets which support the driven parts shown in Figs. 1 and 2. Figs. 5 and 6 are respectively a side elevation and a front elevation of the other bracket which supports the driven parts. Figs. 7 and 8 are opposite face views of the driving mechanism of the switch. Fig. 9 is a side elevation of the driving mechanism shown in Figs. 7 and 8. Fig. 10 is a sectional view on the line 10 10 of Fig. 7. Fig. 11 is a face view of the actuating instrumentalities of the switch with the associated bracket shown in Figs. 5 and 6. Fig. 12 is a sectional view along the line 12 12 of Fig. 11. Fig. 13 is a face view of the actuating instrumentalities similar to Fig. 11, showing their position at their limit of motion opposite to that shown in Fig. 11. Fig. 14 shows the various parts of the switch in perspective in position to be assembled in their proper relations by being moved laterally together without rotation. For convenience the contact-bearing agencies are omitted from Fig. 14. Fig. 15 is an end elevation of the assembled switch, its base being omitted. Fig. 16 is a side elevation of the assembled switch. Fig. 17 is a plan view of the

switch with its associated fuse-block. Fig. 18 is a side elevation of the switch and fuse-block, showing the former inclosed in its cover. Fig. 19 is an end view of the same. 60 Fig. 20 is a longitudinal section along the line 20 20 of Fig. 18, showing by way of explanation the construction of an inclosed fuse.

For convenience the mechanism of this switch may be described in three divisions: 65 first, the driven parts comprising the contacting agencies and their carriers; second, the driving mechanism consisting of the parts which operate upon the contacting agencies to accomplish immediately the making and 70 breaking of the circuit, and, third, the actuating instrumentalities controlled by the operator which compel the operation of the driving mechanism, said driving mechanism in turn communicating its action to the driven 75 parts. The object of this driving mechanism intermediate between the actuating instrumentalities and the driven contacting agencies is to translate the necessarily variant action of the former (it being controlled 80 by hand) to quick decisive action on the part of the latter in order that the make and break of the circuit may be as nearly as practicable instantaneous.

The driven parts comprise the contactors 85 A, the shaft B, the shaft-locking pawl C, and its carrier D, all shown with particular clearness in Figs. 1 and 2. The contactors A consist of cylindrical pulleys fixed upon the extremities of the shaft B. Each contactor 90 carries an oblong metal contact-plate a upon its outer face, said plate having its ends bent over onto the periphery of the contactor, so that there may be metallic connection between diametrically opposite areas of said 95 periphery and between such areas only. The contactor rotates between spring-brushes, (see Fig. 16,) so that when the plate a is in a horizontal position it completes a metallic connection between said brushes, and when 100 the said plate a is in a vertical position said metallic connection is broken. The carrier D, rigid with the shaft B, carries the shaft-locking pawl C, which is pivoted to permit its point to rock toward and away from the shaft. The 105 pawl has a rigid pin b, through which it is rocked. The point of the pawl is laterally offset a slight distance from its carriage to permit it to play against the shaft-stops. Said pawl-carrier D has a projecting tongue 110 f, at which the motive power of the driving mechanism is applied. The shaft B, having

the contactors A and the pawl-carrier D rigid upon it, is journaled in the brackets *c* and *d*, which are conveniently positioned between the contactors to secure compactness in the arrangement of the mechanism.

5 The above-described driven parts being collectively rigid are rotated concurrently by the driving mechanism. It is important that their rotation be divided into successive 10 steps which shall effect alternately the making and breaking of the connection between the brushes embracing the contactors A, as above indicated. To this end the rotation of the driven parts is subjected to a series of 15 arrests resulting from the coöperation of the shaft-locking pawl C with successive fixed shaft-stops *e*, arranged conveniently on a stationary stop-plate E. As shown herewith, there are four such shaft-stops so disposed as 20 to arrest the rotation of the driven parts at successive intervals when the contact-plates *a* are alternately vertical and horizontal relative to the spring-brushes. The stop-plate E is conveniently rigid with the bracket *c*. The shaft- 25 stops *e* are given the form of ratchet-teeth, which engage the point of the shaft-locking pawl. When properly assembled, the stop-plate E and the pawl-carrier D are positioned close together, so that the shaft-locking 30 pawl, offset laterally beyond its carrier, will play against the stops *e*. The pawl coöperates with these stops to arrest the rotation of the driven parts in the forward operative movement of the switch, which for convenience will be styled "positive rotation." The period of inaction succeeding each arrest continues until the pawl is released from its engagement with the shaft-stop, permitting the driven parts to be rotated another 35 step by the driving mechanism.

40 A principal element of the driving mechanism is the spiral shaft motor-spring F, attached at one end thereto, its other end being operatively connected with the shaft, which 45 when wound up tends to impart rotary motion to the shaft through said pawl-carrier. Besides supplying the immediate motive power which rotates the shaft the driving mechanism also releases the shaft-locking 50 pawl from its detaining shaft-stop at appropriate times in the operation of the switch and also receives from the actuating instrumentalities the action which is transmitted to the driven parts.

55 The shaft-locking pawl is released from its detaining shaft-stop by a pawl-controller G. The controller G, rigidly mounted on one end of a hub *g*, which is loose on the shaft, consists of a plate of characteristic shape slotted 60 near its circumference to form a cam-slot *h*, into which projects the pin *b* of the shaft-locking pawl when the parts are assembled. The forward end of the cam-slot *h* (*i. e.*, the foremost end in the positive rotation of the controller) is nearer to the shaft B than is

any other part of the cam-slot. Beginning at said forward extremity the cam-slot recedes gradually from the shaft, reaching maximum displacement therefrom at its rear extremity. Hence during the positive rotation of the controller the shaft-locking pawl, being held stationary by a shaft-stop, the pin *b* in its cam-slot *h* will travel radially outward from the shaft, thereby moving in like manner the pawl C. The rear extremity of the cam-slot is so positioned that when the pin *b* approaches near thereto the point of the shaft-locking pawl will be lifted clear of its engaging shaft-stop. At the other end of the hub *g* from the controller G is fixed a ratchet H. 70 The hub *g*, the controller G, and the ratchet H, being collectively rigid, rotate concurrently, the action of the actuating instrumentalities being applied to the ratchet H. The shaft motor-spring is wound around the hub *g*, one end of said spring being operatively attached to the shaft at the tongue *f* of the pawl-carrier D, the other end of the spring being secured to the ratchet H. 80

When the above-described driven parts 90 and the driving mechanism are in their proper association, the pawl-carrier D and the controller G are positioned close together, the tongue *f* of the carrier projecting into and through the recess *i*, formed in the periphery 95 of the controller. This affords convenient attachment for the end of the motor-spring. The extremities of said recess *i* form shoulders which limit the movement of the tongue *f* to prevent overwinding and unwinding of the motor-spring. 100

The actuating instrumentalities act upon the driving mechanism through the ratchet H. The principal actuating instrumentality is the reciprocating sheave I, which is mounted loosely upon the shaft immediately adjacent to the bracket *d*. The travel of this reciprocating sheave is limited by a projecting lug *j* rigid therewith, which abuts upon the edge of said bracket *d* at each limit of the sheave's reciprocation. This lug is conveniently stamped out of the plate forming the body of the sheave and is turned down near the circumference in such a manner as to project beyond the extreme lateral plane of said sheave upon the side nearest to the said bracket *d*. This sheave, with its associated bracket, is shown at its normal limit of motion when the switch is at rest in Fig. 11 and at its opposite limit of motion in Fig. 13. The sheave is maintained in its normal position with the projection *j* abutting against the lower part of the bracket *d* by the tension of a retracting coil-spring *k*, attached at one end to the bracket and at its other end to the sheave. The concave periphery of the sheave receives said coil-spring, which is held in place by its own tension. The sheave is removed from its normal position to its opposite limit of motion by means 110 115 120 125 130

of a cord or chain *l* attached thereto. When a pull is exerted through the cord or chain *l*, the sheave is rotated about the shaft, the cord being tangential to the circumference of the sheave. It is evident that the pull on the cord opposes the tension of the retracting-spring *k*, whence the sheave will return to its initial normal position when the pull on the cord is relaxed. Upon the face of the sheave 10 farthest from the bracket *d* there is pivoted an actuating spring-pawl *J*. When the parts are properly assembled, the inner face of the sheave is positioned close to a face of the ratchet *H*, so that the actuating-pawl *J* is in a 15 position to engage the teeth of the said ratchet. The actuating-pawl *J* is so disposed that a positive movement of the sheave (i. e., the movement imparted by pulling the cord) drives the point of the 20 pawl against one of the teeth of the ratchet *H* and gives thereto a rotary motion. The reciprocation of the sheave, as shown here- 25 with, is limited by the lug *j* to occur through substantially the space of a quadrant. Hence a single positive movement of said sheave will give to the ratchet rotary movement through a quarter-revolution.

The switch illustrated in the accompanying drawings is a double-pole switch having a 30 pair of spring-brushes *m* embracing each of the contactors *A*. These brushes are suitably associated with the binding-posts *n*, at which electrical connections may be made. The brackets *c* and *d*, the brushes *m*, and the 35 binding-posts *n* are secured to a base *o* in any convenient manner, said base being supplied with suitable apertures for the reception of the wires leading to the binding-posts and for the passage of screws which attach the 40 switch to the ceiling or elsewhere. The mechanism of the switch may be incased in a dome-like cover *p*, which may be held in place by a screw passing through its top into a threaded hole in the top of one of the brackets. An aperture is provided in the top of 45 the cover *p* to permit the cord *l* to pass through.

The operation of the switch is as follows: As already explained, a pull on the cord *l* rotates the sheave through a quarter-revolution, thereby rotating the ratchet *H* through the pawl *J*. Concurrently the hub *q* and the controller *G* are rotated. When this occurs, the shaft-locking pawl *C* is in engagement 50 with a shaft-stop *e*, maintaining the shaft stationary. One end of the spiral motor-spring being operatively connected to the shaft, said end is also stationary. The other end of the spring being attached to the controller *G*, the spring is wound up to an increasing tension as said controller is rotated. While the shaft motor-spring is being wound up, the controller *G* is gradually lifting the 55 shaft-locking pawl *C* from its engagement with the shaft-stop, so that when the said spring has

reached a certain maximum tension the pawl is released, leaving the shaft free to rotate under the impulse of the motor-spring. If for any reason whatever the shaft-locking pawl *C* should fail to be released from its de-

70 taining shaft-stop when the motor-spring

has been wound up, the overwinding of the said spring will be prevented by the rear shoulder of the recess *i* abutting against the tongue *f* of the then stationary pawl-carrier

75

D, further rotation of the driving parts being thereby rendered impossible. When the shaft-locking pawl has been released and the shaft rotated by the motor-spring, the controller will be brought to a standstill by rea-

80

son of the limited movement of the sheave *I*, which can actuate the movement of the driving mechanism through a limited rotation only. The limit of this rotation is reached

85

just after the shaft-locking pawl has been released from its detaining shaft-stop. Consequently during the positive rotation of the shaft and the pawl-carrier the controller *G* remains stationary. The pin *b* then will

80

travel through its cam-slot *h* from the rear to the forward extremity, by which travel the point of the shaft-locking pawl is caused to move inwardly toward the shaft, nearing its limit of inward travel just as it arrives at the next shaft-stop *e*, where it will be engaged

90

anew. If from any cause this engagement should fail to be effected, the rotation of the shaft would be immediately arrested by the tongue *f* abutting upon the forward shoulder of the recess *i*, thereby preventing the un-

95

wincing of the motor-spring. The rotation of the shaft between the release of the shaft-locking pawl and its subsequent reengagement effects either the make or break of the metallic connection between the spring-

100

brushes *m* embracing the contactors, according to the previous position of the contact-plates *a* relative to said brushes. When this has been accomplished, the cord *l* may be relaxed, whereupon the reciprocating sheave

105

will return to its initial normal position, the spring-actuating pawl *J* will be carried to its former position and will there be in position to engage another tooth on the ratchet *H*. Another pull on the cord will initiate a re-

110

petition of the above-described operation, the effect upon the circuit being the opposite to that first produced.

It is highly desirable to combine with this improved snap-switch a fuse-block. A preferred form of the combined snap-switch and fuse-block is shown in Figs. 17, 18, and 19. The base of the switch is secured in any con-

115

venient manner, as by machine-screws, to a platform *q*, of some insulating material, such as porcelain or hard rubber. This platform is channeled at *r r* to permit the wires from the fuses to pass beneath the switch and upward into the apertures which conduct them

120

to the switch binding-posts *n*. Channels *s s*

125

130

are also provided to permit wires to pass from the switch to the main circuit. On said platform *q* adjacent to the switch are fixed the fuse-clips *K*, which receive and secure in place fuses *L*, which are preferably of the inclosed type well known in the art, one of which is shown by way of explanation in Fig. 20 and which forms no part of this invention. In its preferred form each of the clips *K* consists of a single piece of spring copper or brass bent into some such form as is shown in Fig. 19, having two downwardly-extending spring-arms. These arms are curved somewhat at their outer extremities to facilitate the introduction of the fuses to the fuse-seats *t*, which consist of oppositely-disposed bends in the arms, which are adapted to fit closely around the fuse ends when they are in proper position. Each end of the inclosed fuse is capped by a piece of metal *u*, which is connected from within with the fuse, which is completely inclosed in a non-conducting cylinder or pipe. The clips *K* are so disposed that each pair will receive one of these inclosed fuses in such a manner that metallic connection will be established through one clip to the metallic cap *u* embraced by the clip-arms, therefrom through the fuse itself to the metallic cap *u* at its other end, and from said cap to the embracing-arms of the other clip. Each clip is provided with an angle-piece *v*, attached to the platform *q*, which serves to maintain the inclosed fuse in position against lengthwise displacement. Binding-posts *w* are conveniently positioned on the platform *q* and have metallic connection, respectively, with one clip of each pair. With this arrangement a current may enter at one of the binding-posts *w*, travel from there to the associated clip, thence through the clip, the fuse-cap, the fuse, and the other clip, thence through the connecting-wire in a channel *r* to a binding-post *n* of the switch. If the switch be closed, the current will pass through it and out to the line by the wire in a channel *s*.

The switch may be used as a single-pole switch either by removing one of the contactors *A* or by failing to connect up the binding-post on one of the brushes *m*. In like manner the combined fuse-block and switch may be made to serve on a straight or divided circuit. By omitting one of the fuses and its clips and binding-posts or by failing to make the necessary connections with one fuse the fuse-block is adapted to coöperate with a single-pole switch.

I claim as my invention—

1. A snap-switch having, in combination, a shaft carrying the contact making and breaking devices; a shaft motor-spring operatively connected at one end with said shaft; a series of stationary shaft-stops arranged peripherally around the shaft; a pawl-carrier fixed to the shaft having a tongue and a shaft-locking pivoted pawl coöoperating in suc-

sion with said shaft-stops, said pawl having a rigid pin; a step-by-step-moving controller loose on said shaft and operatively connected with the other end of said motor-spring so as to wind up the same, said controller having a pawl-controlling closed cam-slot into which extends said pawl-pin, said pawl being thereby positively disengaged from one of said stops and subsequently positively reengaged with the next succeeding stop at each step of said controller, said cam-slot acting to release the pawl as the controller completes one of its steps in advance and after the motor-spring has been wound up to its maximum tension, whereupon the pawl-carrier and shaft are rotated by the motor-spring until the pawl engages the next succeeding shaft-stop, said controller also having two spaced shoulders between which said tongue lies, one of said shoulders coöoperating with said tongue to prevent the overwinding of the motor-spring, and the other to prevent the unwinding of the motor-spring; a step-by-step-moving ratchet loose on said shaft and rigid with said controller; a reciprocating actuator having a spring-pawl coöoperating with said ratchet to advance it and the controller, thereby winding up the motor-spring; hand-controlled means to advance said ratchet; a spring to return the actuator; and stops to limit the movement of the actuator in both directions.

2. A snap-switch having, in combination, a shaft carrying the contact making and breaking devices; a shaft motor-spring operatively connected at one end with said shaft; a series of stationary shaft-stops; a pawl-carrier fixed to the shaft having a tongue and a shaft-locking pivoted pawl coöperating in succession with said shaft-stops; a step-by-step-moving controller loose on said shaft and operatively connected with the other end of said motor-spring so as to wind up the same, said controller being adapted to positively disengage said pawl from one of said stops and subsequently to positively reengage it with the next succeeding stop at each step, said controller also having two spaced shoulders between which said tongue lies, one of said shoulders coöoperating with said tongue to prevent the overwinding of the motor-spring, and the other to prevent the unwinding of the motor-spring; a step-by-step-moving ratchet loose on said shaft and rigid with said controller; a reciprocating actuator having a spring-pawl coöoperating with said ratchet to advance it and the controller, thereby winding up the motor-spring; hand-controlled means to advance said ratchet; a spring to return the actuator; and stops to limit the movement of the actuator in both directions.

3. A snap-switch having, in combination, a shaft carrying the contact making and breaking devices; a shaft motor-spring oper-

- atively connected at one end with said shaft; a series of stationary shaft-stops; a pawl-carrier fixed to the shaft having a shaft-locking pivoted pawl coöperating in succession with 5 said shaft-stops; a step-by-step-moving controller loose on said shaft and operatively connected with the other end of said motor-spring so as to wind up the same, said controller being adapted to positively disengage 10 said pawl from one of said stops and subsequently to positively reengage it with the next succeeding stop at each step of said controller; coöperating means on said pawl-carrier and said controller to prevent the overwinding 15 of the motor-spring and to prevent the unwinding of the motor-spring; a step-by-step-moving ratchet loose on said shaft and rigid with said controller; a reciprocating actuator coöperating with said ratchet to 20 advance it and the controller, thereby winding up the motor-spring; means to advance said ratchet; means to return the actuator; and stops to limit the movement of the actuator in both directions.
- 25 4. A snap-switch having, in combination, a shaft carrying the contact making and breaking devices; a shaft motor-spring operatively connected at one end with said shaft; a series of stationary shaft-stops; a pawl-carrier fixed to the shaft having a shaft-locking 30 pawl coöperating in succession with said shaft-stops; a step-by-step-moving controller loose on said shaft and operatively connected with the other end of said motor-spring so as to wind up the same, said controller having 35 means to disengage said pawl from one of said stops and subsequently to reengage it with the next succeeding stop at each step; coöperating means on said pawl-carrier and 40 said controller to prevent the overwinding of the motor-spring, and to prevent the unwinding of the motor-spring; and means for moving said controller through its advance steps in succession.
- 45 5. A snap-switch having, in combination, a shaft carrying the contact making and breaking devices; a shaft motor-spring operatively connected at one end with said shaft; a series of stationary shaft-stops; a pawl-carrier 50 fixed to the shaft having a shaft-locking pawl coöperating in succession with said shaft-stops; a step-by-step-moving controller loose on said shaft and operatively connected with the other end of said motor-spring so as to wind up the same, said controller having 55 means to disengage said pawl from one of said stops, when said motor-spring has been wound up; means for reengaging said pawl at the next succeeding stop; means to prevent 60 the overwinding of the motor-spring; and means for moving said controller through its advance steps in succession.
- 65 6. A snap-switch having, in combination, a shaft carrying the contact making and breaking devices; a shaft motor-spring oper-
- atively connected at one end with said shaft; a series of stationary shaft-stops; a pawl-carrier fixed to the shaft having a shaft-locking pawl coöperating in succession with said shaft-stops; a step-by-step-moving controller 70 loose on said shaft and operatively connected with the other end of said motor-spring so as to wind up the same, said controller having means to disengage said pawl from one of said stops when said motor-spring has been 75 wound up; means for reengaging said pawl with the next succeeding stop; means to prevent the unwinding of the motor-spring; and means for moving said controller through its 80 advance steps in succession.
7. A snap-switch having, in combination, a shaft for operating contact making and breaking devices; power-storing means for actuating said shaft when released; a controller for said shaft-actuating means, said 85 controller mounted on the shaft and having means to store the power in the shaft-actuating means and then to release said means to actuate the shaft; hand-controlled means for continuously advancing said controller, said 90 hand-controlled means having backward movement to its original position after each operation of the shaft.
8. A snap-switch having, in combination, a shaft carrying the contact making and 95 breaking devices; means for giving the shaft advance rotation; a stationary shaft-stop adapted to arrest the advance rotation of said shaft; a pawl operatively connected with said shaft to coöperate with said shaft-stop, said pawl having a rigid pin; a tongue rigid with said shaft; a controller capable of relative motion with said shaft, for releasing said pawl from said shaft-stop, said controller having a pawl-controlling closed cam-slot 100 into which extends said pin, said controller having also spaced shoulders between which said tongue lies, the space between said shoulders in excess of the width of said 105 tongue, being less than the length of said cam-slot in excess of the width of said pin.
9. A snap-switch having, in combination, a shaft carrying the contact making and breaking devices; means for giving said shaft advance rotation; a stationary shaft-stop 115 adapted to arrest the advance rotation of the shaft; a pawl operatively connected with the shaft to coöperate with said shaft-stop, said pawl having a rigid pin; a controller for releasing said pawl from said shaft-stop, said controller having a pawl-controlling closed cam-slot 120 into which extends said pin.

In witness whereof I have hereunto signed my name in the presence of two subscribing witnesses.

ALLEN A. TIRRILL.
